Attorney

UNITED STATES PATENT OFFICE.

CHARLES KOFSKE, OF ELBERON, IOWA.

RAIL-JOINT.

SPECIFICATION forming part of Letters Patent No. 782,399, dated February 14, 1905.

Application filed December 1, 1904. Serial No. 235,101.

To all whom it may concern:

Be it known that I, CHARLES KOFSKE, a citizen of the United States, residing at Elberon, in the county of Tama and State of Iowa, have 5 invented certain new and useful Improvements in Rail-Joints; and I do declare the following to be a full, clear, and exact description of the invention, such as will enable others skilled in the art to which it appertains to make and use 10 the same.

My invention relates to improvements in rail-joints; and it consists in the construction, combination, and arrangement of devices hereinafter described and claimed.

15 The object of my invention is to provide a device of this character which will be simple in construction, durable in use, effective in operation, and comparatively inexpensive to manufacture.

20 The above and other objects, which will appear as the nature of my invention is better understood, are accomplished by the construction illustrated in the accompanying drawings, in which—

25 Figure 1 is a side elevation of a rail-joint constructed in accordance with my invention. Fig. 2 is a top plan view of the same. Fig. 3 is a vertical transverse sectional view taken on the line 3 3 of Fig. 1; and Fig. 4 is a de-

30 tail view of one of the fish-plates or coupling-plates removed from the rails.

Referring to the drawings by numeral, 1 and 2 denote the abutting ends of two railway-rails, which are secured upon the usual cross-ties 3.

35 4 and 5 denote my improved fish-plates or coupling-plates, which are secured upon the opposite sides of the ends of the rails by means of bolts 6. These coupling-plates 4 and

40 5 are similar in construction, and each consists of a straight body portion of angular shape in cross-section and formed upon its outer face with a longitudinally-extending enlargement or strengthening portion 7. The

45 strengthening portion or enlargement 7 is curved longitudinally, its upper face or top being inclined upwardly from each end toward

its center, as shown in Figs. 1 and 4. This curved enlargement 7 projects laterally, beyond the body portion of the coupling-plate, 50 which body portion is disposed beneath the head of the rail, as seen in Fig. 3, and not only strengthens the coupling-plate, but also, by reason of its shape, serves as a guard to prevent anything dragging or depending from 55 a car or train from engaging or catching onto said coupling-plate. Owing to the disposition of the body portions of the coupling-plates beneath the head of the rail, they will not be engaged by the flanges upon the wheels 60 of the cars. The bolts 6, which pass through alining openings formed in the ends of the rails and in the coupling-plates, are preferably formed with oval-shaped enlargements 8 adjacent to their heads. These enlargements 8 65 are seated in similarly-shaped sockets 9, formed in the coupling-plate 4, and thereby prevent the bolt from turning when its nut 10 is being applied or removed. The outer lower edges of each of the coupling-plates are formed at 70 suitable intervals with notches or recesses 11, which are adapted to receive the usual spikes 12, which are driven into the cross-ties to secure the said parts to the latter.

From the foregoing description, taken in 75 connection with the accompanying drawings, the construction and operation of the invention will be readily understood without requiring a more extended explanation.

Various changes in the form, proportion, 80 and the minor details of construction may be resorted to without departing from the principle or sacrificing any of the advantages of this invention.

Having thus described my invention, what 85 I claim as new, and desire to secure by Letters Patent, is—

A fish-plate to bear against the web and between the head and base-flange of a rail and formed on its outer side with a longitudinally-extending laterally-enlarged strengthening portion, the upper side of which is below the upper edge of the fish-plate and forms 90 reversely-disposed inclined planes rising from

the ends to the center of the fish-plate, said fish-plate being provided with transverse bolt-openings which extend also through the said laterally-extended enlargement or strengthening portion at points below the upper side of the latter, substantially as described.

5 In testimony whereof I have hereunto set

my hand in presence of two subscribing witnesses.

CHARLES KOFSKE.
